ACCORDION FOLDED PAPER
GARMENT BAG

Arthur C. Johnston, Minneapolis, Minn.

Application December 4, 1944, Serial No. 566,626

1 Claim. (Cl. 206—7)

1

This invention relates to a garment bagging apparatus and method. It is the common practice in suit cleaning and pressing establishments to support a coat, suit or dress on a hanger and then to cover the same with a paper bag. It is a rather slow, awkward and difficult task to get the garment so covered or to get the same into a bag. The bag is usually disposed over the suit or other article of clothing with the open end of the bag at the bottom.

An object of my invention is the provision of a bag for the above and other analogous purposes which has been transversely folded from end to end in a novel manner and to support the bag by the folds thereof to greatly facilitate placing the same over a garment or other object.

It is also an object of this invention to provide a method and apparatus by means of which a bag can be easily and quickly drawn over a suit or other article of clothing supported upon a suitable hanger so that the suit or article is covered by and enclosed in the bag.

It is a further object of the invention to provide an apparatus comprising a container adapted to hold a plurality of collapsed, accordion, folded bags in superposed relation, said bags being folded in longitudinally expansible or extensible condition and disposed with their open ends downwardly, together with means for supporting the lowermost bag from the folds thereof within the mouth of the container and a suit hanger below said container mouth and preferably substantially centrally thereof, said container having an open lower end or mouth through which said bags can be successfully withdrawn, whereby a bag so folded and supported is withdrawn fold by fold from said container and gradually moved downwardly in longitudinally expanded or extended condition over said suit.

It is a further object of the invention to provide a garment bagging apparatus comprising a container adapted to receive a plurality of bags, said bags being folded in longitudinally expansible condition, said container having an opening at its lower end and having supporting means for the bags adjacent thereto, and constructed and arranged so that a bag is supported while gradually withdrawn downwardly through said opening, together with means for supporting a garment hanger adjacent said opening whereby a bag may be withdrawn from said container and moved downwardly over a garment supported on said hanger in longitudinally expanded condition so as to cover or enclose said garment.

It is more specifically an object of the inven-

tion to provide a garment bagging apparatus comprising a container preferably of rectangular form in horizontal cross-section and adapted to receive a plurality of bags in superposed relation, which bags are in substantially flat folded, longitudinally expansible condition with their open ends directed downwardly, said container having an open lower end with means for supporting said bags so that the lowermost bag 10 may be withdrawn through said end, together with a member supported by said container which may extend through said container and bags, said member having means below said container for supporting a garment hanger whereby a bag 15 may be withdrawn downwardly from said container, expanded and moved over a garment supported on said hanger.

These and other objects and advantages of the invention will be fully set forth in the following description made in connection with the accompanying drawings in which like reference characters refer to similar parts throughout the several views and in which:

Fig. 1 is a view partly in front elevation and 25 partly in central vertical section.

Fig. 2 is a view partly in side elevation and partly in central vertical section.

Fig. 3 is a partial vertical section taken on line 3—3 of Fig. 1.

30 Fig. 4 is a perspective view of a folded bag.

Fig. 5 is a vertical section taken on line 5—5 of Fig. 4 as indicated by the arrows.

Fig. 6 is a vertical section taken on line 6—6 of Fig. 4 as indicated by the arrows.

35 Fig. 7 is a perspective view of a hanger supporting member used.

Referring to the drawing, a device is shown comprising a container 10. While this container might be variously formed in the embodiment 40 of the invention illustrated, it is shown of general rectangular form in plan or horizontal cross section. Said container may be open at its top and is shown as provided with a cover or lid 10a. At its bottom container 10 has inwardly 45 extending rather narrow flanges 10b extending inwardly from its longer sides and is open between the inner edges of said flanges. At its ends container 10 is provided with slots 10c having open lower ends and being disposed centrally of the ends of said container. Said container is also provided at its top with an elongated slot 10d disposed centrally of the lid 10a and having its long dimension parallel with the longer sides of said container. Container 10 may be sup- 55 ported at a convenient height in any suitable

manner, and in the embodiment of the invention illustrated it is shown as having a board or plate 11 secured thereto to which is secured a laterally extending supporting member 12. Member 12 can be a part of a bracket attached to the wall or supported from the floor. Container 10 is adapted to receive a plurality of bags 13. Bags 13, as shown, are in comparatively flat folded condition. While said bags could be folded in various ways to be in readily longitudinally expansible or extensible conditions, they are illustrated as formed with transverse accordion-like folds 13a at their opposed sides which extend around the girth of the bags. In other words, the skirt portions of each bag are transversely folded from the closed to the open ends thereof at spaced intervals. The open ends of the bags 13 are directed downwardly and are thus at the lower side of the bags. Said bags 13 are shown as having elongated slots 13b through their closed ends, which slots are shown as of generally rectangular form with the sides thereof parallel to the edges of the bag bottom. It will be observed that the opposed inner edges of the accordion-like folds 13a are spaced apart, as shown in Figs. 5 and 6, so as to provide an axially extending passage 13c immediately underlying and in alignment with the rectangular slot 13b in the closed end of the bag. A member or bar 14 is provided support by container 10, and while it could be supported in various ways in the embodiment of the invention illustrated, it is shown as having members 14a extending perpendicular to its sides, which members have downturned ends 14b adapted to fit over the sides of cover 10a. Bar 14 is shown of rectangular form in transverse cross-section, and members 14a and 14b are thus at right angles to each other. Bar 14 extends downwardly through slot 10d in cover 10a and passage 13c and thence downwardly some distance below the bottom flanges 10b. It will be seen that bar 14 will be held firmly in position by members 14a and 14b. Bar 14 is constructed and arranged at its lower end to support a garment hanger 15. While said bar could be variously so constructed, it is shown as having an arcuate slot 14c in one flat side which will conveniently receive the curved hook-like supporting portion 15a of the hanger 15. The cover 10a has secured at its inner side a flat plate spring 16 of bowed form, the end portions of which are adapted to engage the topmost bag 13 to exert some pressure on the bags and hold them firmly in position with the lowermost bag engaging the flanges 10b.

In operation the bags will be folded and disposed, as shown in the drawing. When a suit, coat or other garment is to be bagged, it is placed on the hanger 15 and the hanger then placed in the slot 14c so that it occupies the position shown in Fig. 1. The operator now takes hold of the lowermost bag at the ends thereof, engaging the same through the slots 10c, and pulls the bag downwardly. The bag readily moves downwardly through the opening between flanges 10b and slides from said flanges, the bag being expanded as it is moved downwardly since the spaced folds therein will be successively engaged and retarded by the flanges. The movement is continued until the whole bag has been withdrawn from container 10 and moved downwardly over the garment on the hanger 15. The bar 14, of course, extends through the axial passages 13c and the slots 13b in all of the bags and the bottom of the bag withdrawn moves

along bar 14 so that the closed end or bottom will eventually move over the handle or supporting portion 15a of the hanger 15, and the bottom of the bag will rest on top of the garment on hanger 15, with the portion 15a projecting through the slot 13b. The garment is now nicely and completely covered by the bag which has been fully extended and the covered garment and bag can be lifted from bar 14 by taking hold of the handle portion 15a. The bags will move or be fed downwardly in the container 10 by the pressure of spring 16. The cover 10a and member 14, together with spring 16, can be conveniently removed and a new supply of bags placed in the container.

While I have disclosed a novel apparatus for dispensing my novel covering bag, it should be obvious that the bag may be used independently of any dispensing apparatus. This could be accomplished by merely taking one of the bags, such as illustrated in Figs. 4, 5 and 6, placing it over a conventional coat hanger 15 having a garment thereon, so that the hooked end 15a projects upwardly through the axial passage 13c and out through the elongated slot 13b. The hooked end 15a and the hanger 15 is then placed over a suitable supporting means and the open end of the bag is pulled down over the garment.

While I have illustrated a bag container having a cover, it is obvious that this cover could be omitted and the upper end of the container left open, without impairing the efficiency of the apparatus or the method of operation. Likewise, while I have shown a spring for the purpose of feeding the bags to the bottom of the container, a weight could be used to accomplish this purpose with equal effectiveness.

It is also important to note that the anchoring of the bar member 14 to the container 10 or other object, prevents wobbling of the bar and assures lengthwise alignment of the bags with the hanger member 15. Of further importance is the fact that when the hook-like supporting portion 15a of the hanger 15 is fitted into the arcuate slot 14c, said hanger 15 will likewise be held rigidly in alignment with the bags as they are pulled downwardly and expanded over the hanger and garment being supported therefrom.

From the above description it will be seen that I have provided a simple, convenient and efficient method and apparatus for easily and quickly covering a suit or other garment or placing a bag thereover. The operation of withdrawing the bag and moving it over the garment in expanded condition can be very quickly performed. The garments can thus be very quickly covered. The method, bag and apparatus have been amply demonstrated in actual practice and found to be very successful and efficient.

It will, of course, be understood that various changes may be made in the form, details, arrangement and proportions of the apparatus and in the steps and sequence of steps of the method without departing from the scope of applicant's invention, which, generally stated, consists in a method, bag and apparatus capable of carrying out the objects above set forth, such as disclosed and defined in the appended claim.

What is claimed is:

A garment enclosing paper bag rectangular in cross-section and having a closed end and an open end, said closed end having a centrally disposed aperture the side walls of said bag being each provided with a plurality of transverse accordion folds which join at their ends to ex-

tend around its girth from the closed to the open end thereof, said joining folds providing for collapsing of the bag with its open end opening into the bag between the folds to facilitate initial admission of a hanger supported garment into that end of the bag and to the closed end thereof, whereby the bag may be readily distendable over and about the garment by reason of said joining folds with the hanger projecting through the aperture in the closed end of the 10 bag.
